10h. The folded zones of portions 10j are now disposed at the outer sides of the parts 10h and the zones 10na and 10nb of portions 10b at each side of the lines 10n are now disposed respectively along the end 10g and the sides 10h respectively at the inner sides thereof and in the corners at the inside of the box. This is shown in Fig. 8.

The box is now at its front portion substantially in the form shown in Fig. 8 while the rear portion is still in its blank form with the side parts 10h and parts extending therefrom folded upwardly. At the ends of the rectangular portions 10i are portions 10o of rectangular form, the same being shown as square and these are creased to fold along the dotted lines 10p respectively. A top portion 10q of rectangular form similar to bottom portion 10m extends from the rear part 10i at the side thereof opposite bottom 10m and this top 10q has extending therefrom at its sides, portions 10r. The portions 10r at their inner ends connect to the portions 10o along the lines 10s respectively, which lines 10s are creased for folding. The portions 10r are shown as somewhat curved at their outer ends and these are creased to fold along the lines 10t which extend outwardly and rearwardly from the upper corner of the rear wall 10i. The blank is also creased for folding along the four sides of the bottom 10m and the top 10q. With the box in the form above mentioned with the front portion as shown in Fig. 8 and the rear portion lying open, the operator now places his hands along the sides of the box and places his fingers on the outer sides of the zones 10oa at the outer sides of lines 10p respectively. This causes the zones 10o to fold inwardly along the lines 10p and simultaneously swings the rear wall or part 10i upwardly about its bottom edge. The box is now substantially in the position shown in Fig. 6. The operation continues and the operator swings the top 10q forwardly so that the folded zones 10o now are disposed inwardly of the side portions 10h. The operator now presses downwardly on the side flaps 10r of the top and these fold along the lines 10t so that the triangular zones 10ra are disposed at the inner sides of flaps 10r respectively and at the outer sides of the side parts 10h respectively. The operator now swings the flap 10a downwardly about its inner edge and this is disposed at the front of the front part or wall 10g, as shown in Fig. 1. The box is now in its closed and operative position. The folding thus comprises two operations; the first one where the operator presses on the zones 10ja and swings the front part or wall 10g to vertical position and presses downwardly the triangular portions 10b folding them along the lines 10n respectively and disposing the same at the inner sides of the front part or wall 10g and the side parts or walls 10h respectively. In the second operation the operator as above described presses on the under side of the zones 10oa and swings the rear part or wall 10i to vertical position simultaneously folding zones 10o inwardly along lines 10p and disposing the same at the inner sides of the side parts or walls 10h and then continuing the motion by pressing downwardly on the side flaps 10r and the end flaps 10a. The box can then be very quickly brought from the flat condition of the blank to the full operative position. Actual tests have shown that the box can be brought to operative position in about half the time that a box having the hooked portions insertable through slits can be brought to operative position.

In using the box the article to be enclosed therein will preferably be placed in the box when

the front part of the box has been folded upwardly and the flaps 10b are folded downwardly in final position. If a cake is to be placed in the box it can now be placed on the bottom 10m. 5 When the operator then places his fingers on the under side of the zones 10oa and swings the rear wall 10i into vertical position and brings the top 10 the inwardly advancing folded edge thereof which extends along line 10p remains substantially at the outer sides of the bottom 10m so that the cake is not touched. The top is swung over the box and the side and front flaps are pressed downwardly and the box is thus brought to closed 15 position. Such boxes are usually and preferably tied with a string to hold the flaps closed.

The blank used to form the box is of comparatively simple form and can be easily produced by simple dies. The blank can be creased in the usual manner. In addition to the advantages of the blank and dies and the easy and quick folding operation the box produced has great strength and is much more rigid and durable than the boxes of the prior art. The pieces 10b which are folded downwardly at the inner sides of the box at the front corners and the zones 10ja which extend along the outer sides of the side walls 10h strongly reinforce the front corners and give great rigidity and strength to the box. There are five thicknesses of material at the front parts of the side walls 10h. This gives great strength to the box against being crushed vertically. The folded in zones 10o which are disposed at the inside of the walls 10h at the rear ends thereof and the zones 10ra which are disposed at the outer sides of said side parts or walls 10h also give great strength to the box at its rear corners. It will be noted that there are five thicknesses of material at the rear portions of the side walls 10h, as shown in Fig. 5. The flaps 10a and 10r tightly close the box and also add to the strength and rigidity of the same.

The box of this invention is so easily and quickly folded into operative position that it is not necessary to have a stock or reserve supply of complete boxes on hand. With the boxes of prior art it has been customary in bakeries and other establishments using boxes, for the employes when not particularly busy to fold up some boxes so as to have a supply of completed boxes on hand. These take up considerable space and it is objectionable to have a big supply of them ready. In the boxes of the prior art, particularly those having the hook portions which are placed in slits in the box, it often occurs that the hook portions are torn or the slits are torn in the folding of the box. Such boxes have to be discharged and are thus a waste and a loss. There is no chance or probability of the box of the present invention being so torn or damaged and the loss in such boxes which is often times considerable is eliminated. Another advantage of the box of this invention is that the cake or other article can be very easily removed. When the box is opened 60 by swinging the top upwardly and outwardly the top and the rear side are brought into substantially horizontal position. The cake can thus be removed with a sliding motion, the same being merely slid along the bottom of the box and out over the top. This feature is also often important in removing laundered shirts and other articles from the box.

From the above description it will be seen that we have provided a very simple, efficient and practical box and method of making the same.

The box is simpler than those of the prior art and can be made less expensively. The box can be folded into operative position in much less time than the boxes of the prior art and when so folded it constitutes a much stronger and more rigid box than the boxes of the prior art. Furthermore the blank used is of such a form that it can be cut with little or no waste of material. The flap 10a at one end of the blank can be formed by the portion cut out between parts 10b. The invention has been amply demonstrated in actual practice and found to be very successful and efficient.

It will of course be understood that various changes may be made in the form, details, arrangement and proportions of the device and in the steps and sequence of steps of the method without departing from the scope of applicants' invention, which, generally stated, consists in a method and device capable of carrying out the objects above set forth, such as disclosed and defined in the appended claims.

What is claimed is:

1. A box, such as a cake box, made of stiff sheet material and adapted to be folded into shape from a blank to form an empty box having in combination, a piece of stiff sheet material having front, rear and side substantially rectangular parts extending upwardly from a rectangular bottom and disposed substantially at right angles thereto, a top part of rectangular shape extending from the top edge of said rear part, portions with sides adjoining said rear part and side parts respectively and of the same width as said side parts, said portions being folded inwardly respectively along lines making a substantially 45 degrees angle to the sides of said portions respectively and lying along the inner sides of said side parts, said top having flaps extending outwardly from the sides thereof joined to said portions at the inner ends thereof, each having a crease at its rear portion extending from the rear corner of said top at substantially the same angle to the side of said portion as said lines, said flap being folded along said crease so that it extends along the outer sides of said portion and side part respectively.

2. A box, such as a cake box, adapted to be folded into empty box form from a flat blank made of stiff sheet material having in combination, a rectangular bottom part, front, rectangular side and rear walls extending upwardly from the sides of said bottom part, rectangular zones between the ends of said walls at the front and rear, said zones at the front being folded along diagonal lines and disposed at the outside of said side walls, triangular pieces extending outwardly from said front zones and front wall creased along lines extending from their apices to the ends of said front wall and aligned with said ends respectively, said triangular portions being folded along said crease and disposed inwardly and vertically along the front and side walls, said rectangular zones at the rear being folded along diagonal lines extending from the rear corners of said bottom and disposed at the inside of said side walls substantially parallel thereto, said box having a rectangular top portion extending from the top of said rear wall and having substantially rectangular flaps at the sides thereof having substantially the same width as said rectangular zones, said flaps being joined to the ends of said rear zones and creased along a line extending in the same direction as the line of fold of said rear zones, said flaps

being folded along said crease and disposed vertically along the outside of said side walls and rear zones respectively with the portion between said crease and the attached end of said flap disposed inside of the remainder of said flap.

3. A box, such as a cake box adapted to be folded into operative empty form from a flat prepared blank of stiff sheet material having in combination, a piece of stiff sheet material having front, rear and side rectangular walls and a rectangular bottom, said walls being bent upwardly substantially at right angles from said bottom, means for holding the front and side walls in vertical position, rectangular zones extending from the rear ends of said side walls respectively and of substantially the same width as said side walls and also being connected to said rear wall, a top portion extending from the top of said rear wall, said top portion having flaps at its sides connected to and of substantially the same width as said zones respectively, said flaps being creased and folded along lines extending from the rear top corners of said rear wall diagonally outward toward the free ends of said flaps, said zones being disposed along the inner side of said side walls and said flaps being folded along said creases and extending along the outer sides of and parallel to said side walls and said zones.

4. A box made of stiff sheet material adapted to be folded into shape from a blank initially creased along certain lines to form an empty box having in combination, a piece of stiff sheet material having front, rear and side parts and a rectangular bottom to which said parts are connected, said parts being substantially rectangular and bent upwardly from said bottom at substantially right angles, a top portion rectangular in plan connected to and extending from the top of said rear part, rectangular portions having sides connected to the ends of said rear part and to the rear ends of said side parts respectively, said rectangular portions being respectively folded along a diagonal extending from the rear corners of said bottom respectively to the opposite corner and being disposed inside of said side parts respectively, said top having extensions at its sides integral with and of the same width as said rectangular portions folded along a line extending outwardly from the inner corner of said top portion substantially parallel to said last mentioned diagonal, and extending respectively along the outer side of said side parts and inside of said extensions at each side of said box.
